UNITED STATES PATENT OFFICE.

WILLIAM T. CONLEY, OF CAMBRIDGE, MASSACHUSETTS.

SHINGLE.

Application filed August 23, 1923. Serial No. 658,998.

To all whom it may concern:

Be it known that I, WILLIAM T. CONLEY, a citizen of the United States, residing at Cambridge, in the county of Middlesex and State of Massachusetts, have invented a new and useful Shingle, of which the following is a specification.

This invention relates to shingles and more particularly to locks for flexible shingles.

The object of the invention is to provide a shingle of this character so constructed as to cause the interlocking of the various shingles and preserve the relation between them and which avoids curling of the lower edges.

Another object is to so construct a shingle as to cause it to lie in close contact with the roof and subjacent shingles producing a leak proof roof of long life.

Another object is to provide a shingle having a lock extending across the entire butt which is formed of the same material as the shingle and as an addition thereto avoiding the necessity of cutting into the shingle and the consequent weakening thereof and which may be quickly put in place and presents when applied a neat appearance and yet has great strength.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 represents a plan view of a portion of a roof formed from shingles constructed in accordance with this invention.

Fig. 2 is a bottom plan view.

Fig. 3 is a plan view of one of the shingles with the locking tab shown in open unfolded position.

Fig. 4 is a transverse section taken on the line 4—4 of Fig. 2; and

Fig. 5 is a section taken on the line 5—5 of Fig. 2.

In the embodiment illustrated the shingle 1 constituting this invention is constructed of the usual asphaltic composition, metal or other flexible material and is shown made

substantially rectangular or diamond shaped in accordance with the general practice although it will be understood that the shape of the shingle may be varied as desired.

The shingle 1 has the butt or lower corner thereof extended at opposite sides to form tabs 5 and 6 which with the butt of the shingle form a flap 2 foldable along the dotted line 3 to lie when in operative position under the body portion of the shingle, the tabs 4 and 5 being pointed as shown at 4 so that when the flap 2 is folded inwardly against the body of the shingle the inner inclined edges of said tabs will be flush with the adjacent edges of the shingle body while the outer inclined edges thereof will facilitate the insertion of one corner of the adjacent shingles as is shown clearly in Fig. 2.

The formation of the tab 2 as an integral part of the shingle strengthens the shingle and provides when interlockingly engaged with the adjacent shingles a secure lock.

The locking flap 2 extends across the entire butt of the shingle and avoids all necessity of cutting into the shingle such as is ordinarily found necessary with shingles of this character. The lock so formed can be quickly put into place on the roof and when the shingles are connected the securing means are invisible as shown in Fig. 1. 85

In shingling a roof with flexible shingles 1 embodying this invention, the shingles are laid diagonally as shown in Figs. 1 and 2. Each course is laid by placing the shingle of the next upper course over a shingle of the next lower course in position for the corners of the shingles of the lower course to be inserted between the ends of flap 2 of the shingle of the upper course as shown in Fig. 2 so that the shingles are all interlockingly connected thus preventing curling of the shingle edges and providing a leak proof roof.

Various changes in the form, shape, proportion and other minor details of construction may be made without departing from the principle or sacrificing any of the advantages of the claimed invention.

I claim:

An individual diamond-shaped shingle having unbroken edges and its butt extended laterally at both edges to form a locking tab, said tab being foldable under the body of the shingle to provide pockets to receive and interlockingly engage the edges of ad- 110

adjacent shingles, each end of said tab being inclined inwardly in opposite directions from its center, the inclined inner portions conforming to the adjacent side edges of the 5 shingle whereby the tab is concealed when folded and engagement with edges of adjacent shingles facilitated:

In testimony that I claim the foregoing as my own, I have hereto affixed my signature in the presence of two witnesses.

WILLIAM T. CONLEY.

Witnesses:

HERBERT W. ALLEN,
HELENA G. GAVIN.
